Primary Examiner — Clare E Heflin(74) *Attorney, Agent, or Firm* — Heslin Rothenberg Farley & Mesiti P.C.(57) **CLAIM**

The ornamental design for a wall luminaire, as shown and described.

DESCRIPTION

FIG. 1 is a perspective view of the wall luminaire of the present design;

FIG. 2 is a front elevation view thereof;

FIG. 3 is a rear elevation view thereof;

FIG. 4 is a right side elevation view thereof, the left side elevation view being a mirror image thereof;

FIG. 5 is top plan view thereof; and,

FIG. 6 is a bottom plan view thereof.

The broken lines in the figures illustrate portions of the wall luminaire that are not claimed.
